SHOE

James E. Quinn, Normandy, and Hugh F. Elliott,
University City, Mo., assignors to International
Shoe Company, St. Louis, Mo., a corporation of
Delaware

Application February 7, 1936, Serial No. 62,744

3 Claims. (Cl. 36—45)

This invention relates to improvements in shoes.

An object of the invention is to provide a shoe having a continuous quarter without a back seam shaped to conform to the back line of the last over which it is made to form a smooth finish at the heel and a smooth heel seat, in combination with a quarter lining having a seam extending from the lower edge thereof and terminating below the upper edge to form a curved portion that will fit snugly against the inner surface of the counter.

Another object of the invention is to provide a shoe having a continuous quarter with the back line molded to conform to a standard last over which the shoe is made with a fitted quarter lining having a substantially coincident upper edge with the upper edge of the quarter, thereby providing a close fitting top line to the finished shoe having a snug ankle fit when worn.

Additional advantages of the construction will be apparent from the following detailed description of one embodiment thereof, taken in connection with the accompanying drawings, in which:

Fig. 1 is a view of the quarter blank.

Fig. 2 is an edge view of the same.

Fig. 3 is a view of the quarter lining blank.

Fig. 4 illustrates a portion of the mechanism employed for molding the back line of the quarter.

Fig. 5 is a view on the line 5—5 of Fig. 4.

Fig. 6 is a further illustration of the mechanism for molding the back line of the quarter in molding position.

Fig. 7 is a view similar to Fig. 5, but with the mechanism shown in the position of Fig. 6.

Fig. 8 shows a molded quarter blank.

Fig. 9 is an edge view of the quarter blank.

Fig. 10 is a view particularly illustrating the conformation of the molded section of the quarter blank, the bulge being indicated to the right of the line x—x, showing the degree of deformation of the original quarter blank.

Fig. 11 is a view of the quarter lining finished.

Fig. 12 is an edge view thereof.

Fig. 13 is a section view of the assembled parts of the shoe on the last.

Fig. 14 is an illustration of the rear portion of the finished shoe.

In constructing the shoe of the invention, the quarter 1 of the shoe is blanked out of a continuous piece of material, thus avoiding the usual back seam and providing a shoe section that may be assembled with the shoe vamp in the usual manner. After the quarter blank has been formed it is molded, the mechanism for this pur-

pose being shown sufficiently for clarity of description in Figs. 4 to 7 inclusive of the drawings.

The mechanism for the molding operation to impart the bulge or fullness in the blank consists of a machine familiar in the art of shoe making and is ordinarily referred to as a "crimping" machine. This machine, for the present use, consists of heated stationary jaws 2 spaced apart to provide an opening therebetween. Above the stationary jaws 2 is a reciprocating blade 3 having a convex lower edge. The quarter blank is stretched across the jaws 2 and the blade 3 is moved downwardly to the position illustrated in Figs. 6 and 7. The material of the quarter blank is thus formed to provide a bulge or fullness along the back line of the shoe by the impingement of the material against the jaws 2 by the blade 3. It will be understood that, in order to give permanence to the set of the blank, it is preferred that the jaws 2 be heated, resulting in the blank holding the bulged formation after it has been removed from the machine. The finished quarter blank is shown in Figs. 8 to 10 inclusive of the drawings, from which it will appear that along the center line of the wheel portion of the quarter blank there is a convex bulge, the extent of which is indicated particularly in Fig. 10 as lying to the right of the line x—x. The degree of curvature can be regulated by the form of the edge of the blade 3, so that the quarter blank will have a curve conforming to the back line of a standard last over which the shoe is made, and so that the shoe, when completed, will have a curvature at the back line that smoothly fits the outer curvature of the counter.

The quarter lining 4 is blanked out, as shown particularly in Fig. 3, and has an upper line of curvature which in blank form substantially follows the line of curvature of the quarter. In order to provide for the necessary conformation of the quarter lining to the curve of the back line of the shoe, the quarter lining is formed with a V-shaped cut-out 5, the base of which extends from the lower edge of the blank to a point substantially intermediate of the height of the blank, with the apex of the cut-out substantially on the back line of the shoe. In finishing the quarter lining the V-shaped cut-out is closed and seamed by the seam 6, producing the formation of the quarter lining, as particularly shown in Figs. 11 and 12. After the preparation of the quarter section and the quarter lining element, the parts are assembled in the usual manner over a last, it being understood that the lining is stitched to the quarter and the parts then

stitched to the usual vamp of the shoe to form a closed shoe upper. The closed shoe upper is assembled on a last 7 in the usual manner with the counter 8 inserted between the lining and 5 quarter, the lower edge of the quarter and lining being turned in, as at 9, over the insole 10 to form a heel seat.

Since the correct conformation of the rear portion of the shoe to the back line of the last 10 is provided for in the formation of the quarter and the lining, the assembled upper may be readily pulled over the last without stretching the parts, thus facilitating the operation of lasting and, at the same time, providing a smooth 15 finish to the back portion of the shoe and a smooth, tight top line for the finished shoe, as well as providing a lower edge to the quarter and lining assembly, so that it may be turned in to form a smooth contour at the heel seat.

20 What we claim and desire to secure by Letters Patent is:

1. A shoe construction including a continuous outer quarter having an exteriorly convex bulge along the center line of the heel portion comprising material displaced from the plane of the remainder of the outer quarter, a quarter lining having the contour of its upper edge substantially the same as the contour of the upper edge of the outer quarter, and means connecting said 25 outer quarter and quarter lining along their upper edges, said quarter lining having a closed cut-out at its lower edge, said bulge and said

closed cut-out providing a space between the outer quarter and the quarter lining to accommodate a counter.

2. A shoe construction including a continuous outer quarter having an outward bulge or fullness along the center line of the heel portion comprising material displaced from the plane of the remainder of the outer quarter, a quarter lining stitched to said outer quarter having substantially the same upper line contour as the 10 upper line contour of the outer quarter, and provided with a seamed cut-out extending upwardly from its lower edge to well within the boundaries of the outer quarter to form a constriction disposed similarly to the bulge of the outer quarter, 15 said bulge and constriction providing a space for a counter.

3. A shoe construction including a continuous outer quarter having an exteriorly convex bulge along the center line of the heel portion comprising material displaced from the plane of the remainder of the outer quarter, a quarter lining having the contour of its upper edge substantially the same as the contour of the upper edge of the outer quarter, and means connecting said outer quarter and quarter lining along their upper edges, said quarter lining having a shortened lower edge, said bulge and said shortened lower edge providing a space between the outer quarter and quarter lining to accommodate a counter. 20
